UNITED STATES PATENT OFFICE.

CHARLES E. FISCHER, OF CHICAGO, ILLINOIS.

PUZZLE.

SPECIFICATION forming part of Letters Patent No. 672,895, dated April 30, 1901.

Application filed November 23, 1900. Serial No. 37,493. (No model.)

To all whom it may concern:

Be it known that I, CHARLES E. FISCHER, a citizen of the United States, residing at Chicago, in the county of Cook and State of Illinois, have invented a new and useful Puzzle, of which the following is a specification.

This invention relates to puzzles; and the object is to provide a simple, cheap, and amusing puzzle.

With the above object in view the invention consists in the novel features of construction hereinafter fully described, particularly pointed out in the claims, and clearly illustrated in the accompanying drawings, in which—

Figure 1 is a plan view of a puzzle embodying my invention; Fig. 2, a transverse sectional view taken on the line 2 2 thereof. Fig. 3 is a perspective view of one of the gates.

Referring now more particularly to the accompanying drawings, A designates a base-board, preferably rectangular in outline and having secured about its edges flanges B, which prevent the marbles with which the

puzzle is played from rolling from the board. Positioned upon the board are pins or projections C, so arranged as to form a circuitous path. At one end of the board a plurality of open-ended compartments D are formed

by pins E, placed in alinement. Each compartment bears the name of one of the nations of the world which participated in the capture of Pekin—namely, England, Russia, America, Germany, and France—while the word

“Pekin” is printed in large letters across the board at the inner ends of said compartments, as illustrated. The compartments are closed by swinging gates, as illustrated, each gate being composed of a piece of metal bent in-

termediate its ends to form a loop F, which is placed upon one of the pins, so as to pivot the gate. This loop is placed nearer one end of the gate than the other, so as to provide a gate portion G, closing one of the compartments,

and a gate portion H, abutting one of the pins of the next compartment, so as to close said compartment also and prevent the opening of the gate of that compartment until the gate portion G of the compartment on the left is

swung inwardly to open that compartment. 50 Thus each compartment excepting the one on the left is provided with a double gate, and the gates of the compartments must be opened successively, beginning with the one on the left, or the first of the series. 55

Adjacent to the opposite end of the board the word “Home” is printed, and from this point the marbles I must be started to begin the solution of the puzzle. These marbles I correspond in number to the nations represented, and each marble bears a color, said colors corresponding to the colors of the several compartments.

The object is to roll the marbles by tilting the board through the circuitous path and 65 lodge the same in the proper compartments, the game being designed to represent the taking of the gates of Pekin by the foreign nations.

Having thus fully described my invention, 70 what I claim as new, and desire to secure by Letters Patent, is—

1. A puzzle comprising a base-board and a plurality of balls adapted to move thereon, and bearing distinguishing marks or characters, in combination with a series of pins secured to said board to form a circuitous path, 75 a plurality of compartments arranged at one end of the board and bearing distinguishing marks or characters corresponding with the 80 marks or characters carried by the balls, and swinging gates controlling the entrance to said compartments, substantially as described.

2. A puzzle consisting of a base-board and a plurality of balls adapted to move thereon, 85 in combination with a series of pins arranged upon the base-board to form a circuitous path, a plurality of compartments formed at one end of the board, and swinging gates controlling the entrance of said compartments, each 90 gate having a portion closing the entrance to the next compartment and positioned in advance of the gate of that compartment, substantially as described.

CHARLES E. FISCHER.
